UNITED STATES PATENT OFFICE.

JOHN F. WILLIAMS, OF KANSAS CITY, KANSAS, ASSIGNOR TO THE ECONOMY GAS LAMP COMPANY, OF KANSAS CITY, MISSOURI.

DESIGN FOR A LAMP-FIXTURE.

SPECIFICATION forming part of Design No. 30,149, dated February 7, 1899.

Application filed December 24, 1898. Serial No. 700,291. Term of patent 14 years.

To all whom it may concern:

Be it known that I, JOHN F. WILLIAMS, a citizen of the United States, residing at Kansas City, in the county of Wyandotte and State 5 of Kansas, have invented and produced a new and original Design for a Lamp-Fixture, of which the following is a specification.

My present invention relates to a new and original design for lamp-fixtures, of which the 10 following is a specification, reference being had to the annexed drawing, wherein the frame is shown in elevation.

The fixture consists of the members A and B, connected at one end by a curved section 15 C, member A being connected at the opposite end to a fitting or casting D. An arm E extends up from the fitting, said arm being

curved, as shown, and having connected to its upper end a pipe F, which in turn is connected to a reservoir G. An arm H extends 20 down from the lower end of the fitting D, the lower portion of said arm being curved and carrying at its outer end a burner-support I.

Having thus described my invention, what I claim is—

The design for a lamp-fixture as herein shown and described.

In witness whereof I hereunto set my hand in the presence of two witnesses.

JOHN F. WILLIAMS.
